UNITED STATES PATENT OFFICE.

LOUIS G. BOSTEDO, OF CHICAGO, ILLINOIS.

OIL-BURNING FURNACE.

Application filed February 9, 1922. Serial No. 535,154.

To all whom it may concern:

Be it known that I, Louis G. BOSTEDO, a citizen of the United States, residing at Chicago, in the county of Cook and State 5 of Illinois, have invented certain new and useful Improvements in Oil-Burning Furnaces, of which the following is a specification.

This invention relates to improvements 10 in furnaces of that type which are designed to utilize kerosene or cruder forms of oil as fuel, and has reference more particularly to that type of such furnaces wherein the oil is supplied to the fire box of the furnace 15 in the form of a continuously burning jet.

One object of the invention is to provide an improved oil burning furnace of that type that does not require the use of moving mechanism such as fans, blowers, pumps 20 or other extraneous mechanical means for forcing and spraying the oil into the fire box, but effects such injection of the oil and air to support combustion through the agency of a steam jet.

Another object is to provide a furnace of 25 the character specified wherein the steam generated in the furnace may also be utilized to supply the water required for the generation of steam in situations where the 30 water is not under main pressure or the main pressure is insufficient, and wherein the steam thus used is also returned to the furnace and its heat thus conserved.

Other objects are to provide an improved 35 steam generator specially adapted to the purposes and conditions of my oil burning furnace; to provide an improved automatic regulator for the water supply to the steam generator; and to provide an improved 40 flame guard for controlling the access of the burning jet to the boiler of the steam generator.

Other objects and attendant advantages 45 of the invention will be apparent to persons familiar with this art from the accompanying description, taken in connection with the drawings, wherein I have illustrated one practical and workable embodiment of the invention, and in which—

Fig. 1 is a front elevation of a portion of 50 a furnace of the round type, showing my improved oil inducing and burning apparatus applied thereto, parts of such apparatus appearing in vertical section;

Fig. 2 is a horizontal section taken sub- 55 stantially on the offset line 2—2 of Fig. 1;

Fig. 3 is a fragmentary view of the lower portion of the oil tank, showing a steam heating coil therein;

Fig. 4 is a central vertical section on the 60 line 4—4 of Fig. 2; and

Fig. 5 is a fragmentary front elevation 65 of the boiler housing showing the adjustable flame guard or damper for the front opening thereof.

The present invention has been designed chiefly to supply domestic heating plants for use in dwelling houses, apartments, and the like; and its chief characteristics comprise a boiler located in the fire box of the 70 furnace, which maintains a head of steam, and a steam pipe leading out therefrom, which sucks the oil from an oil tank and forces it into an atomizer equipped with a burner nozzle. Another steam pipe may 75 be used to induce a stream of air into the atomizer in order that the atomizing may be done in large part by a fluid favoring combustion, instead of by steam alone, which tends to smother the fire. A third steam 80 pipe is preferably used to heat the oil in the oil tank and on its way to the atomizer; while a fourth steam pipe is used to inject the water into the boiler in situations where the main pressure is not available or sufficient 85 for this purpose.

Referring to the drawings, 6 designates the cylindrical wall of a domestic furnace of the ordinary round type, equipped as usual with suitable fire brick lining 7, and 90 8 designates the fire chamber or box within the same. In situations where the oil burner of the present invention is applied to coal burning furnaces, the usual grate bars of the latter will be removed, and the 95 ash pit opening, with the door thereof removed, may be utilized in association with the atomizer and burner nozzle. In the present drawings I have shown the wall of the fire box as provided with a round opening 9 through which the burning jet from the nozzle of the atomizer enters the fire box, the outer end of said opening being extended around the burner nozzle by an inwardly tapered ring 10 attached to the 100 furnace wall 6 and providing, with the burner nozzle, an annular opening for the induction of atmospheric air to support combustion.

Located centrally within the fire box 8 is 110 a steam boiler in which steam is generated to serve as the agent for inducing, atomiz-

ing and spraying the oil and directing the burning jet into the fire box. This boiler is preferably encased within an upright circular boiler housing 11 that is preferably disposed coaxially with the fire box itself and is formed with a side opening 12 of somewhat greater diameter than the fire box opening 9 and located directly opposite and in coaxial alinement with the latter. 13 5 designates a water supply pipe that extends through and is supported by the walls 6, 7 and 11, and at its inner end carries a short upright cylinder 14 forming in part the casing of an automatic water regulator 10 valve. Connected into and extending upwardly from the cylinder 14 is a vertical tube 15 on the upper end of which is mounted the lower head 16 of a boiler cylinder 17, this latter being provided with a similar 15 upper boiler head 18. Connected into and depending from the lower boiler head 16 is a circular group of water legs 19 closed at their lower ends by caps 20. All of these water legs, together with the central tube 15 20 which also has the function of a water leg, communicate freely at their upper ends with the boiler cylinder or tank 17. Fitted coaxially within the cylinder 14 is a tube 21 closed at its lower end by a threaded plug 22 and communicating at its upper end with the central tube or water leg 15. In the side of the tube 21 which lies opposite the delivery end of the water pipe 13 is a vertical 25 row of ports 23 which are adapted to be covered and uncovered by a sliding piston valve 24 mounted on the lower end of the stem 25 of a ball float 26 that lies within the boiler tank 17, and has a diameter slightly less than the diameter of the latter. The 30 mechanism last described obviously functions as an automatic regulator to maintain a substantially constant amount of water in the boiler. As the generation and consumption of steam increases, the water level of 35 course falls, and this lowers the valve 24, thus bringing an increased number of water supply ports 23 into action, and thus restoring the normal level of the water. Conversely, when the generation and consumption 40 of steam decreases, the water level in the tank 17 rises, the valve 24 rising at the same time and reducing the number of active water supply ports. The travel of the valve 24 is so limited by the plug 22 and a pin 26' on the float that it can never entirely overrun the ports 23 in either direction.

It may also be noted that the water legs 45 19 are located directly behind the opening 12 of the boiler housing, through which opening the intensely hot flames and gas of the burning jet are free to impinge directly on said water legs, by reason of which, and of the further fact that the said legs present a large surface area to the external

heat relatively to the volume of water contained therein, the generation of steam is practically instantaneous, or of the well known "flash" order as soon as the burner gets into operation.

In the upper head 18 of the boiler tank is a central T coupling 27 open at its lower end to the steam chamber by lateral ports 28. From this T coupling there extend downwardly within the boiler housing 11 a 75 pair of steam pipes 29 and 30. From the lower end of pipe 29 there extends outwardly through the walls of the boiler housing and fire box a pipe 31 which leads into an atomizer that is located directly in front of the fire box opening 9; and from the lower end of the other vertical pipe 30 there extends outwardly through the walls of the boiler housing and fire box a similar steam pipe 32, which also leads into the 80 atomizer.

Fig. 2 shows in horizontal section a practical construction of the atomizer, the same comprising a central body or shell 33 having a forwardly directed burner nozzle 34 and a pair of oppositely extending lateral branches 35 and 36. Into the under side of the branch 35 there is led an oil supply pipe 37 (Fig. 1) terminating in a nozzle 38 located opposite and delivering the oil to the flaring mouth of an elbow-shaped central oil delivery pipe 39, the delivery end or nozzle of which lies coaxial with the burner nozzle 34. The steam pipe 32 leads, through a T coupling 40 equipped with a cut off valve 41, into the outer end of the atomizer branch 35, delivering the steam around the oil nozzle 38, the flow of the steam thence through the delivery pipe 39 inducing the oil with it, and the commingled steam and oil being discharged in the form of a spray at the tip of the delivery pipe 39.

On the under side of the branch 36 I preferably provide an air supply opening 42, best shown in Fig. 1; and into the outer end of the branch 36 is connected the steam supply pipe 31, the same being equipped with a cut off valve 43 and terminating in a nozzle 44 located directly opposite to and in line with a tapered induction tube 45, the flow of steam through the latter inducing an inflow of air through the opening 42. From the induction tube 45 the steam and air flow into an oil jet regulating device, this latter consisting of a tubular member 46 slidably fitted within the body and burner nozzle of the atomizer, and provided on the one side with an opening 47 for the passage of the steam and air into the same, and on the other side with a slot 48 to accommodate the steam and oil delivery pipe 39. The forward end of the regulator tube 46 extends somewhat beyond the forward end of the steam and oil delivery pipe 39 and is tapered inwardly and forwardly around the latter,

thereby providing an annular passage for the steam and air. This annular passage is enlarged or constricted by adjusting the regulator tube forwardly or rearwardly, which may be done by means of an adjusting screw 49 engaged with the outer end or head of the regulating tube and rotatably mounted in a detachable cap 50 on the outer end of the atomizer body, and provided with 10 a hand wheel 51.

In situations where there is no available water main pressure for supplying water to the boiler, or where the main pressure may be inadequate, I interpose in the water 15 supply pipe 13 a steam injector which is shown in Fig. 1 and designated as an entirety by 52. The structural features of the injector herein shown are old and known, and constitute no part of my present invention. The injector is supplied with 20 steam by a branch pipe 53 which may lead from the pipe 31, as indicated in Fig. 2.

The oil supply pipe 37 leads from a point near the bottom of an oil tank indicated at 25 54 in Fig. 3; and in order to preliminarily heat the oil in the tank and on its way to the atomizer, I preferably tap one of the main steam supply pipes, such as the pipe 32, by a branch pipe 55 which extends along- 30 side the oil pipe 37 to a heating coil 55' in the tank 54, preferably encircling the lower end of the oil pipe 37 and thence back on the opposite side of the oil pipe 37, whence it is extended and connected into the water supply pipe 13, as clearly shown in Fig. 1. The two limbs of the steam pipe 55 which lie alongside the oil pipe 37 are, with the latter, preferably encased in a tube or wrapper 56 of heat insulating material.

40 To start the furnace in operation it is, of course, necessary to provide means for initially raising steam in the boiler, and for this purpose I preferably employ an annular gas burner 57 located in the bottom of the 45 boiler housing 11 directly beneath the water legs 19; said burner being provided on its upper side with a series of jet nozzles 58 adapted to direct the gas flames against the lower ends of the water legs 19. The burner 50 57 is, of course, provided with a suitable gas supply pipe 59 conveniently led in through the lower ends of the furnace and boiler housing walls, as clearly shown in Fig. 4.

55 In the water supply pipe 13 is interposed an ordinary cut off valve 60, and also a check valve 61.

To control the intensity of the fire, I provide in association with the opening 12 in 60 the boiler housing a manually controllable flame damper. This flame damper may be of any practical form or structure but in Figs. 4 and 5 I have shown a preferred type of flame damper comprising a pair of op- 65 ositely facing substantially semi-circular

slabs or plates 62 of fire resisting material that are suspended from a pair of pivot pins 63 just above the opening 12 so as to hang freely from the latter and be normally self-closing, as indicated in Fig. 5. The hinge lugs of the two plates or slabs 62 carry intermeshing pinions 64, and one of the pivot pins 63 is extended in the form of a shaft through the furnace wall and carries a sprocket wheel 64' that may be connected 70 by a section of sprocket chain 65 and wires 66 to a regulating sprocket (not shown) in a floor above the basement.

When the furnace is idle, the water is turned off by closing the cut off valve 60. 80 In starting the furnace in operation, the water is first turned on until the boiler is filled up to the normal operating level, and then turned off while raising steam by means of the gas burner. As soon as the atomizer delivers a jet of oil and steam through the burner nozzle the jet is ignited, and then, or shortly thereafter, the water is again turned on and its feed to the boiler 85 regulated and controlled automatically by the float and regulator valve. In the normal operation of the furnace, the generated steam pressure is automatically maintained at or slightly below the water pressure where the latter is supplied under the pressure 90 of a water main. When the apparatus is first installed and tested, the atomizer regulator 46 is set to give the proper ratio of steam and oil or steam, air and oil to secure the thorough atomizing of the latter, and thereafter the volume of flame directed through the opening 12 can be nicely regulated by the flame damper 62; and the amount of heat furnished by the furnace 95 can be controlled entirely by the manipulation of the flame damper. This adjustment of the flame damper indirectly regulates the amount of oil induced through varying the volume and pressure of the steam. The induction of air into the atomizer by and with a jet of steam is not essential to the operativeness of the device, since sufficient air to support combustion is induced by the jet through the air induction ring 10 and opening 9 surrounding the burner nozzle, but the described induction of air to the atomizer facilitates the breaking up of the oil and also boosts the combustion, and hence is preferably used. The 100 induced air also cools down the steam and thereby prevents the formation of carbon in the atomizer nozzle. The oil level is preferably maintained slightly below the level of the atomizer, which enables a low pressure steam jet to efficiently serve as the 105 oil-inducing agent, and at the same time avoids all danger of accidental flooding such as sometimes occurs where the oil is introduced under a hydrostatic head or by means 110 of a pump or fluid pressure.

While I have herein shown and described one embodiment of my invention which has been demonstrated in practice and found to satisfactorily effectuate the stated purposes and objects of the invention, it is manifest that the details of structure and arrangement may be varied from those shown without involving any departure from the principle of the invention or sacrificing any of the advantages thereof. Hence, I reserve all such variations and modifications as fall within the spirit and purview of the appended claims.

I claim:

- 15 1. In an oil burning furnace, the combination with a fire box formed with an opening in a wall thereof, of a steam generator located in said fire-box, an atomizer formed with a burner nozzle located opposite and directed into said opening and toward said steam generator, said atomizer having an air induction opening, an oil supply pipe leading into said atomizer, a pipe from said generator leading into said atomizer and supplying steam for the induction of oil, and another pipe from said generator leading into said atomizer for the induction of air.
- 20 2. In an oil burning furnace, the combination with a fire-box formed with an opening in a wall thereof, of a steam generator located in said fire-box, an atomizer located opposite said opening and formed with an opening for the induction of air, said atomizer terminating in a burner nozzle directed into said opening and toward said steam generator, an oil supply pipe connected into said atomizer, means for supplying an oil and air inducing flow of steam from said generator to said atomizer, a water supply pipe connected into said generator, an injector interposed in said water supply pipe, and a steam supply pipe from said generator to said injector.
- 25 3. In an oil burning furnace, the combination with a fire chamber formed with an opening in a side wall thereof, of a boiler housing in said fire chamber formed with an opening opposite said fire chamber opening, a boiler in said boiler housing, an atomizer terminating in a burner nozzle directed into both of said openings and toward said boiler, an oil supply pipe connected into said atomizer, and a steam supply pipe from said boiler to said atomizer.
- 30 4. In an oil burning furnace, the combination with a fire chamber having an opening in a side wall thereof, of a boiler housing in said fire chamber formed with an opening opposite said fire chamber opening, a boiler in said boiler housing, an atomizer mounted externally of said fire chamber and terminating in a burner nozzle directed into both of said openings, an oil supply pipe connected into said atomizer, a steam supply pipe connected into said atomizer, a

pipe from said boiler to said atomizer for the induction of oil, and means for varying the volume of flame admitted through said boiler housing opening whereby to regulate the amount of oil drawn into the atomizer through variations in the volume and pressure of steam generated in said boiler.

5. In an oil burning furnace, the combination with a fire chamber formed with an opening in a side wall thereof, of a boiler housing in said fire chamber formed with an opening opposite said fire chamber opening, a boiler in said boiler housing, an atomizer mounted externally of said fire chamber and terminating in a burner nozzle directed into both of said openings and toward the lower portion of said boiler, an oil supply pipe connected into said atomizer, a steam supply pipe from said boiler to said atomizer, and an adjustable damper for said boiler housing opening for adjusting the effective area of the latter.

6. In an oil burning furnace, the combination with a fire chamber formed with an opening in a wall thereof, of a steam boiler located in said fire chamber, an atomizer located opposite said opening and terminating in a burner nozzle directed into the latter, an oil supply pipe connected into said atomizer, means for supplying an oil inducing current of steam from said boiler to said atomizer, and a gas burner for initially generating steam in said boiler.

7. In an oil burning furnace, the combination with a fire chamber formed with an opening in a wall thereof, of a boiler housing in said fire chamber having an opening located opposite the fire chamber opening, a steam boiler within said housing, an atomizer located exteriorly of said fire chamber and terminating in a burner nozzle directed into both of said openings, an oil supply pipe connected into said atomizer, a steam supply pipe from said boiler to said atomizer, and a gas burner located in said housing beneath said boiler.

8. In an oil burning furnace, the combination with a fire box formed with an opening in a wall thereof, of a steam boiler located in said fire box, an atomizer located opposite said opening and terminating in a burner nozzle directed into the latter, an oil supply pipe connected into said atomizer, a steam supply pipe from said boiler to said atomizer, a water supply pipe leading into said boiler, an injector interposed in said water supply pipe, and a steam pipe leading from said boiler to said injector.

9. In an oil burning furnace, the combination with a fire box formed with an opening in a wall thereof, of a steam boiler located in said fire box, an atomizer located opposite said opening and terminating in a burner nozzle directed into the latter, an oil supply pipe connected into said atomizer, a

water supply pipe leading into said boiler, and automatic means in said boiler for regulating the supply of water thereto.

10. In an oil burning furnace, the combination with a fire box formed with an opening in a wall thereof, of a steam boiler located in said fire box, an atomizer located opposite said opening and terminating in a burner nozzle directed into the latter, a water

supply pipe for said boiler, an oil tank, an oil supply pipe leading from said tank into said atomizer, a steam pipe from said boiler to said atomizer, and a steam pipe from said boiler leading through said oil tank for heating the oil in the latter and connected, into said water supply pipe.

LOUIS G. BOSTEDO.
